APPARATUS FOR AND METHOD OF
SMOOTHING PUMP BORESMichele Caserta, Detroit, Mich., assignor to
Thompson Products, Inc., a corporation of
Ohio

Application April 17, 1944, Serial No. 531,430

14 Claims. (Cl. 51—34)

1

This invention relates to an apparatus for and to a method of smoothing pump and other bores without substantially altering the generated bore shape or contour.

In the construction of rotary vane pumps such as described and claimed in my co-pending application Serial No. 397,763, filed June 12, 1941, the pump bore is so contoured as to make the operation of the pump substantially non-pulsating. This is accomplished by forming the bore with a normal cross-sectional contour that comprises a pair of opposite circle arcs having different radii but a common axis of generation, a pair of opposite Archimedes spirals intermediate the circle arcs, and four parabolic spirals joining the ends of the circle arcs to the ends of the Archimedes spirals, all of the curves having a common axis of generation and common tangents at their points of juncture. A bore of such a contour is rather difficult to form and to smooth properly, since the tolerances must be held very close indeed and owing to the non-cylindrical nature of the bore, special tools and grinding devices have to be employed.

In accordance with my present invention, the bore of a pump, or of a pump liner, is formed in a series of operations. In the case of a pump liner, a solid round billet is first bored to form a cylindrical bore using substantially the maximum length of radius that can be employed and yet have the cylinder lie wholly within the desired contour of the finished bore. Ports are next cut in the side wall of the liner and the proper contour of the bore formed therein by cam turning or grinding, or by broaching. In this operation, the bore is formed accurately to the desired contour, but to a thousandth of an inch or so under the final dimensions, just sufficient to permit the desired amount of smoothing in the subsequent honing operation.

In the smoothing operation, to which the present invention more particularly relates, the smoothing is effected by a pair of abrasive surfaces, which are extensible outwardly along the diametral plane in which they are mounted to bear against the internal bore surface of the pump liner with the desired amount of pressure. To accomplish this, a device is used that simulates in some respects the rotor and vanes of a rotary vane pump, the abrasive surfaces being provided by strips of honing stones or other abrasive material carried externally by a pair of radially extensible blades mounted in an adjustable assembly within a diametral slot in the end of a rotatable spindle. The assembly includes means

2

for forcing said blades radially outwardly and for operating said means to adjust the position of said blades until they span a diametral length equal to the diameter of the finished bore. The smoothing operation is effected by rotating and reciprocating the spindle carrying the blades relative to the pump liner. In a smoothing operation as carried out by a device of my invention, the radially extensible blades oscillate as a unit in the diametral slot of the spindle end to follow the contour of the bore as initially formed in much the same way as do the slidable vanes of the rotor in the finished bore of a pump liner during the operation of the pump. Accordingly, it is possible by the use of my invention to smooth a generated pump bore having a constant diametral dimension through its axis of generation in a very simple and efficient manner, while holding the bore to very close tolerances.

It is therefore an important object of this invention to provide an apparatus for smoothing bores of pumps, pump liners or the like where such bores are of a generated contour having a constant diametral dimension through a common axis of generation.

It is a further important object of this invention to provide a simple and rapid method of smoothing the internal surfaces of pumps, or pump liner bores, and the like where such surfaces are formed from a plurality of curved surfaces having a common axis of generation and common tangents at their lines of juncture, but are not cylindrical.

Other and further important objects of this invention will be apparent from the disclosures in the specification and the accompanying drawings.

On the drawings:

Figure 1 is a side elevational view of an apparatus embodying my invention;

Figure 2 is a fragmentary, front elevational view to illustrate the operation of the clamping mechanism for holding said pump liner in position during the honing operation;

Figure 3 is a fragmentary, top plan view of the pump liner clamping and holding means;

Figure 4 is a fragmentary, side elevational view of the pump liner clamped in position;

Figure 5 is an enlarged elevational view of a finished pump liner;

Figure 6 is a diagrammatical cross-sectional view of the pump liner of Figure 5 indicating the axis of generation and the radii of the arcs and curves of which the pump bore is composed;

Figure 7 is a partly diagrammatic view of a

cylindrical billet being initially reamed to a cylindrical bore;

Figure 8 is a fragmentary, enlarged, sectional view taken substantially along the line VIII—VIII of Figure 10, with the honing device at the lowest point of its reciprocating movement and with the honing strips radially retracted prior to the start of the smoothing operation, with parts in elevation;

Figure 9 is a view similar to Figure 8 but with the honing device at the top of its strip and with the honing strips in operative position, with parts in elevation;

Figure 10 is a top plan view of the honing device;

Figure 11 is a sectional view taken substantially along the line XI—XI of Figure 9;

Figure 12 is a sectional view taken substantially along the line XII—XII of Figure 8 with parts in elevation; and

Figure 13 is a sectional view taken substantially along the line XIII—XIII of Figure 9.

The reference numeral 10 (Figure 1) indicates generally a platform or base from which is mounted an upstanding post 11 for supporting the honing apparatus of my invention. Said apparatus includes a work table 12 adjustably mounted upon said post 11 and adapted to be held in adjusted position thereon by means of a thumb screw 13.

The work table 12 is provided on its upper face with an annular, recessed holder 13 for receiving the lower end of a pump liner 14. Said holder 13 may be integral with the work table 12 or fixedly attached thereto by any suitable means. The holder 13 is provided with a cylindrical socket 15 for receiving the lower edge of said pump liner 14 with a snug fit. Both the table 12 and holder 13 are apertured, as indicated by the dotted line 16, to permit the honing device to project upwardly therethrough into the interior of the pump liner 14.

Also supported upon the table 12 is a clamping mechanism, indicated generally by the reference numeral 17. Said clamping mechanism 17 (Figure 2) comprises a pair of upstanding plates 18 secured to said work table 12 in any suitable manner and having a spacer block 19 positioned therebetween. A rearwardly and upwardly inclined arm 20 is rigidly held at its lower end between said spaced plates 18 by means of pins 21 and 22 extending therethrough. At the upper free end of said arm 20 there is pivotally mounted to said arm, by means of a pivot pin 23, a pair of lever arms 27 having bowed-apart end portions 24 and 25. A strip 26 extends between said end portions 24 and 25 inwardly of their extremities. A lever arm 29, having at its upper free end a handle 28, is pivotally mounted at its lower end, as by means of a pivot pin 31, between said upstanding plates 18. Said arm 29 is also pivotally connected near its free end, as at 33, to a pair of short links 30. The other ends of said links 30 are pivotally connected as at 32 to the arms 27. The outer free ends 24 and 25 of the lever arms 27 carry members 34 and 35, respectively, that are provided with dependent clamping portions 36 and 37, respectively, adapted to overlie and engage the upper edge of a pump liner 14. Said cross strip 26 is provided with a downwardly extending pin 38 for reception in a recess or socket 39. There is one such pin receiving recess or socket 39 in each end of a pump liner 14 (Figure 5).

As shown in Figure 2, when the clamping and

holding mechanism is in its operative position, the pin 38 extends into the pin receiving socket 39 and the pump liner engaging portions 36 and 37 are clamped over the upper edge of a pump liner 14. In this position the lever 27 is substantially horizontal and the lever 29 lies forward of the axis of the pivot pin 32, which may be considered to be the dead center point of the mechanism. Accordingly, in its normal position, the clamping mechanism can be thrown out of clamping engagement only by a manual pull upon the handle 28 to draw the lever arm 29 back and thus lift the arm 27. The clamping mechanism, in its inoperative position, is illustrated in dotted lines in Figure 2.

There is also mounted for adjustment upon the post 11 (Figure 1) a driving mechanism, indicated generally by the reference numeral 40, which comprises an arm 41 provided with a bore 42 through which said post 11 extends. A thumb screw 43 is provided for locking the arm 41 in adjusted position upon said post. A motor 44 is attached to said arm 41 at one side of the post 11. Said motor has a vertical drive shaft 45 near the lower end of which is mounted a pulley 46. Said pulley 46 is adapted to drive, by means of a belt 47, a second pulley 48 mounted upon the lower end of a spindle 49 that extends through a bore 50 in the free end of said arm 41. A second pulley 51 is mounted upon the extreme lower end of said motor shaft 45 and is adapted to drive a disk 52 mounted upon a pin 53 from the side of the motor housing. Since the pulley 51 and disk 52 are in planes at right angles to each other, a pair of small pulleys 54 and 55 are used to guide the driving belt 56 that extends around said pulley 51 and disk 52. Said small pulleys 54 and 55 are supported from the motor housing by means of a branched supporting bracket 57.

The pulley 48 is mounted upon the lower end of the spindle 49 so that said spindle 49 may be rotated by the motor 44 acting through the drive pulley 46 and the drive belt 47. The hub 58 of said pulley 48 is keyed on said spindle 49 by means of a spline 59 so as to permit reciprocal movement of said spindle 49 along its vertical axis, while the hub 58 is held against displacement vertically between the horizontal arms of a U-shaped bracket 60 fixedly secured to said arm 41. The horizontal arms of the bracket 60 are apertured, as at 61, to permit free passage of the spindle 49 therethrough.

A sleeve 62 is mounted upon said spindle 49 near its upper end between a pair of fixed collars 63 and 64. Said sleeve 62 is loose upon the spindle 49 but because it is held between the collars 63 and 64 is capable of transmitting axial movement to said spindle 49. Such axial movement is accomplished through a crank arm 65, one end 66 of which is adjustable in a slot 67 of said disk 52. The other end of said crank arm 65 is connected by means of a pivot pin 68 to one end of a rod 69. The other end of said rod 69 is provided with an eye 70 which engages a shaft 71 journaled in the spaced dependent sidewalls 72 of said table 12. A pinion 73 is fixedly mounted upon said rotatable shaft 71, so that as the disk 52 is revolved, the crank arm 65, acting through the rod 69, causes said pinion 73 to revolve first in one and then in the other direction. Said pinion 73 meshes with a rack 74 formed in the sleeve 62, whereby said sleeve 62, and consequently the spindle 49, is caused to reciprocate vertically when the motor 44 is running.

As best shown in Figures 8 to 13, inclusive, the

upper end of the spindle 49 is provided with a diametral slot 75 which extends clear to the end of said spindle and is partially closed by an overlying disk 76 held thereon by means of screws 770 (Figure 10). Within said slot 75 is mounted the smoothing or honing mechanism, indicated generally by the reference numeral 77. Said mechanism 77 comprises a pair of members 78 and 79, held against axial displacement between the bottom 80 of said slot 75 and the underside of the cover disk 76 but bodily movable laterally within said slot 75. Each of said members 78 and 79 is longitudinally grooved for receiving abrasive strips 81 and 82, respectively. Said strips 81 and 82 may suitably comprise honing stones and are replaceable when worn too thin.

The members 78 and 79 are provided along their inner edges with opposed tapered extensions 83 and 84 (Figure 11) that serve to give said members wider areas of contact with the walls of the slot 75 and thus prevent said members from wobbling or becoming cocked in said slot. Each of said members 78 and 79 is further provided at longitudinally spaced points along their lengths with inwardly directed abutment portions 85 and 85a, and 86 and 86a for a purpose that will later appear. Said members 78 and 79 are also provided with transverse slots 87 and 87a (Figures 8 and 9) for a purpose that will presently be described.

Means are provided for forcing said members 78 and 79 laterally apart within the slot 75. Such means include an integrally formed member 88 (Figure 12) provided with a slot 189 extending laterally completely therethrough. Said member 88 (Figure 8) is formed with a wedge-shaped portion 89 at its upper end, having upwardly convergent outer faces 90 and 90a, and at its lower end with a wedge-shaped portion 91 having also upwardly convergent edges 92 and 92a. A rod 93 is provided with a lower threaded portion 94 that is adapted to be engaged in a threaded bore provided for that purpose in the upper end of said member 88. Said rod 93 carries at its upper free end a knurled head 95 to facilitate its manual operation. At its lower end the rod 93 is provided with a portion 96 of reduced diameter which is freely received in a socket formed in a floating bridge member 97. Said bridge member 97 extends through the slot 189 in said member 88 and the ends of said bridge member extend freely into the slots 87 and 87a in said members 78 and 79.

With the honing mechanism 77 in the position shown in Figure 8, that is with the members 78 and 79 in their inwardly retracted state, a pump liner 14 can be slipped over the upper end of said mechanism and clamped in place upon the work table 12. The threaded shaft 93 is then manually turned to move the honing strip carrying members 78 and 79 outwardly into the position illustrated in Figure 9. Upon threading said shaft 93 into the member 88, said member 88 is drawn upwardly and the action of the tapered surfaces 85 and 85a, and 86 and 86a, working upon the corresponding abutments 85 and 85a and 86 and 86a cause said members 78 and 79 to be spread apart laterally until the surfaces of the honing strips 81 and 82 are in working engagement with the inside surface of the pump liner 14. The bridge 97, into which the lower end of the shaft 93 extends, prevents longitudinal movement of said shaft 93 when it is being threaded into or out of the member 88 and thus causes relative axial movement of the

member 88. The degree of taper of the surfaces 85 and 85a and of the surfaces 86 and 86a, is, of course, the same so that the abrasive strips 81 and 82 are maintained exactly parallel to each other throughout their length while being moved radially outwardly during manual operation of the rod 93.

In preparing a pump liner 14 for the honing operation about to be described, a solid cylindrical billet may first be provided with an eccentric but truly cylindrical bore 100 (Figure 7) by means of a reamer 101. Said bore 100 is then re-formed to the desired contour of the finished pump liner, as for instance to the contour indicated by the dotted line 102. This may be accomplished by broaching. Ports 103 and 104 are cut into the wall of the pump liner to the size and shape desired, either before or after the broaching operation. The pump liner 14 is also provided, prior to the honing operation, with the pin receiving recesses 39 (Figure 5) extending inwardly from each of the end faces on the thicker side of the pump liner. These recesses 39 also serve an alignment purpose in the assembly of the pump liner in a pump such as shown in my co-pending application Serial No. 397,763, filed June 12, 1941.

The bore 102 at the start of the honing operation is slightly undersize as compared with the final dimensions of the bore 102a (Figure 6) in the finished pump liner. The contour of the bore will, in accordance with known principles, have a common axis of generation, indicated by the letter A (Figure 6) which will be concentric with respect to the outer cylindrical surface 105 of said pump liner. All of the diameters of the pump bore 102a passing through said common axis of generation A will, of course, be of equal length.

In accordance with one method of obtaining a non-pulsating pump, the contour of the bore 102a is formed by a pair of opposite circle arcs, defined at their extremities by the points 106 and 107, and by the points 108 and 109, formed with unequal radii R and r, respectively. Intermediate the extremities of said arcs 106-107 and 108-109 are a pair of Archimedes spirals 110-111 and 112-113, which are joined to the extremities of the circle arcs by four parabolic spirals, 106-112, 107-110, 108-111, and 109-113. All of these arcs and curves have a common axis of generation A, and they also have common tangents at their points of junction. All of the diameters passing through said common axis of generation A, such as the diameters 106-A-108 and 107-A-109 are of equal length.

It will be understood, of course, that the particular contour of the bore forms no part of the present invention, but is described merely for the purpose of illustration to show the type of work for which my honing apparatus is particularly adapted. While capable of honing the surface of a truly cylindrical bore, the apparatus here described is more particularly designed for the honing of non-cylindrical bores, which are nevertheless formed with a common axis of generation and with diameters of constant length.

The operation of my honing device will now be described:

A pump liner 14 is inserted over the upper end of the spindle 49 carrying the honing device with the honing strips 81 and 82 in retracted position, as illustrated in Figure 8. The pump liner 14 fits snugly into the recess 15 of the holder 13. The clamping mechanism 17 is then moved into clamping position, as illustrated in full lines in

Figure 2, the liner 14 having previously been turned until the centering and aligning pin 38 can be inserted into the socket or recess 39. The lever 29 is then thrown over beyond the dead center to clamp the pump liner 14 securely in the holder 13.

Next, the rod 93 is manually turned to draw upwardly the blade spreading mechanism 77 and thus force the honing strips 81 and 82 outwardly into firm working engagement with the interior surface of the bore 102a.

The motor 44 is next started up to begin the honing operation. During the operation a cooling fluid, such as kerosene, may be run over the entire honing mechanism. The skirt 121 protects the driving mechanism from the kerosene. The length of the reciprocating stroke of the spindle 49 should previously have been adjusted, by adjustment of the eccentric pin 66 in the slot 67, so that at the extreme positions of the spindle in its stroke, the honing strips 81 and 82 always span the full length of the pump liner 14, that is, at the lowermost position of the spindle, the upper ends of the honing strips 81 and 82 (Figure 8) do not pass below the upper end of the pump liner 14, while at the extreme uppermost point of travel of the spindle 49, the lower ends of said honing strips 81 and 82 still lie below the bottom edge of the pump liner 14. This provision is important if a straight walled bore, rather than a bell mouth bore, is to be obtained. The amount of the reciprocation of the honing strips 81 and 82 is preferably such as not to bring the ends of said strips within the cut-out wall portions forming the ports 103 and 104, since there would then be a tendency for the ends of the strips, if coming within said cut-out portions, to catch on the edges of the port openings and either be damaged or wear away said edges unevenly.

In usual practice, the amount of abrasion of the wall of said bore 102 effected by the honing operation is of the order of 0.001 inch and is not intended to accomplish other than a sufficient smoothing operation to make possible a smooth sliding fit between the bore and the vanes of the rotor when the pump is assembled in an operating condition.

As the spindle reciprocates, it is also rotated by the drive including the pulleys 46 and 48 and the driving belt 47. The rate of rotation is suitably in the neighborhood of 400 R. P. M., but slower or faster rates of revolution can be employed depending upon the type of work being done. As the spindle rotates, the entire blade carrying mechanism 77 oscillates as a unit laterally in a series of diametral planes, the honing strips 81 and 82 remaining in fixed spaced relationship relative to each other. The movement of the assembly is similar to that of the vanes of a rotor in the operation of a vane type pump. During such displacement along their diameters, the members 78 and 79 slide within the slot 75 with their upper edges confined by the closure 76 and with their lower edges resting against the lower wall 80 of said slot 75. As previously explained, the extended contact surface areas provided by the extensions 83 and 84 between said members 78 and 79 and the lateral walls of said slot 75 tend to prevent wabbling or cocking of the members within the slot.

During the honing operation, it may be desirable to adjust the honing strips 81 and 82 outwardly into closer pressure relationship with the surface of the bore undergoing the smoothing operation. This can be accomplished without stop-

ping the motor 44 by merely grasping the knurled end 95 and giving the rod 93 a twist. With a fair amount of experience, an operator can easily determine to what extent to adjust the diametral span of the abrasive strips 81 and 82, and adjustments are made whenever necessary during the operation of the device without interrupting rotation of the spindle. Ordinarily, the honing operation requires a very brief period.

10 The necessity for the smoothing operation arises from the fact that the bore cannot be perfectly formed in the first instance by broaching or the like. Also, there is usually some distortion due to the heat treatment step that follows broaching.

15 It is important to note that the method herein described does not control the shape of the bore other than to insure constant diametral length, but is effective only in giving to the bore a smooth 20 finish without substantially altering the generated bore shape, and in making sure that all diameters through the axis of generation A will have exactly the same length. This insures that the 25 pump vanes will have exactly the same end clearance in all positions of the vanes within the bore.

25 If desired, the work table 12 can be swung very slightly one way or the other to cause the abrasive strips 81 and 82 to bear more heavily when riding across the ports 103 and 104, thus giving more 30 clearance at those points and closer clearance in the pumping zones between ports, when the liner is assembled and the pump is in operation.

In order to permit the honing strips to be 35 changed without taking the closure disc 76 off and lifting the mechanism 77 out of the slot 75, the rim of the annular holder 13 (Figure 3) is cut away at opposite sides as at 120, to the lower edge of the liner. The strips 81 and 82 can thus be removed laterally and changed with a minimum of effort.

40 It will, of course, be understood that various 45 details of construction may be varied through a wide range without departing from the principles of this invention and it is, therefore, not the purpose to limit the patent granted hereon otherwise than necessitated by the scope of the appended claims.

What I claim is:

1. Apparatus for honing the internal surface of 50 a hollow article, the bore of which has been formed with joined dissimilar surfaces of generation having a common axis of generation and diameters of constant length, said apparatus comprising a rotatable and reciprocable member having a diametrically extending slot, radially adjustable blades slidably positioned for movement in said slot and having strips of honing material projecting outwardly therefrom, means for adjusting said blades to bring said honing material 55 into working contact with said internal surface and hold said blades after adjustment in rigidly fixed spaced relationship, and means for rotating and reciprocating said member within said bore to effect the honing of said surface to smooth the 60 same without materially altering the curvatures of said surfaces of generation, said blades being freely oscillatable in said slot during said honing operation to permit said honing material to follow the contour of said internal surface.

70 2. Apparatus for honing the internal surface of 75 a hollow article, the bore of which has been formed with joined dissimilar surfaces of generation having a common axis of generation with all of the diameters of said bore passing through said axis of constant length, said apparatus com-

prising a rotatable and reciprocable member having a diametrically extending slot, radially adjustable blades slidably positioned in said slot and having strips of honing material projecting outwardly therefrom, means for adjusting said blades to bring said honing material into working contact with said internal surface including means for holding said honing material in adjusted extended position with the desired contact pressure against said surface, and means for rotating and reciprocating said member within said bore to effect the honing of said surface to smooth the same, said blades and blade adjusting and holding means being freely oscillatable in said slot to permit said honing material to follow the contour of said internal surface without materially altering the curvatures of said surfaces of generation.

3. Apparatus for honing the internal surface of a hollow article, the bore of which has been formed with joined dissimilar surfaces of generation having a common axis of generation and constant diametral dimensions, said apparatus comprising an adjustable supporting fixture for holding said article with the bore thereof unobstructed, a rotatable and reciprocable member having a diametrically extending slot, an assembly slidably positioned in said slot and having strips of honing material projecting outwardly therefrom, means associated with said assembly for extending said blades to bring said honing material into working contact with said internal surface, and means for rotating and reciprocating said member within said bore to effect the honing of said surface to smooth the same, said assembly being freely oscillatable in said slot to permit said honing material to follow the contour of said internal surface without materially altering the curvatures of said surfaces of generation.

4. In an apparatus of the class described, a member having a diametral slot, radially opposed blades in said slot carrying outwardly projecting honing surfaces, tapered rigid elements between said blades and in contact therewith for moving said blades into radially extended positions, and an adjusting member cooperating with said tapered elements to effect such radial extension of said blades and said tapered elements, said blades being oscillatable as a unit in said slot along a diametral plane without change in diametral length.

5. In an apparatus of the class described, a member having a diametral slot, radially opposed blades in said slot carrying outwardly projecting honing surfaces, means associated with said blades for moving said blades into radially extended positions and providing a rigid backing for said blades, and an adjusting member cooperating with said means to effect such radial extension of said blades, said blades and said rigid backing means being oscillatable in said slot along a diametral plane without change in diametral length.

6. In an apparatus of the class described, a member having a diametral slot, radially opposed blades in said slot carrying outwardly projecting honing surfaces, tapered elements between said blades for moving said blades into radially extended positions and providing a rigid backing for said blades, and a manually operable threaded adjusting member cooperating with said tapered elements to effect such radial extension of said blades, said blades and tapered elements being oscillatable as a unit in said slot along a diametral plane without change in diametral length.

7. In an apparatus of the class described, a

cylindrical member having a slot extending diametrically therethrough, a pair of radially opposed blades mounted in said slot for movement therein along a diametral plane, honing strips carried by said blades and projecting outwardly therefrom, tapered elements for engaging internal faces of said blades, adjusting means associated with said tapered elements for moving said blades radially outwardly uniformly of their lengths, said adjusting means including an extension projecting beyond an end of said cylindrical member and manually operable during rotation of said cylindrical member, said honing strips, tapered elements and adjusting means constituting a unit of rigidly fixed diametral length for any given adjustment and said unit being movable in said slot, and means for rotating said cylindrical member to cause said honing strips to smooth an internal bore with which said strips may be adjusted into contact.

8. In an apparatus of the class described, a rotatable and reciprocable shaft having an open ended slot extending through the axis thereof, a closure member for the end of said slot and an assembly retained by said closure member and freely oscillatable in said slot as a unit of fixed diametral length during operation of said shaft including outwardly projecting parallel strips of abrasive material for the smoothing of internal surfaces.

9. In an apparatus of the class described, a rotatable and reciprocable member having a slot extending through the axis thereof and an assembly freely oscillatable in said slot during operation of said member including outwardly projecting strips of abrasive material for the smoothing of internal surfaces, said assembly also including tapered elements associated with said strips for moving the same into outwardly projecting position and means for actuating said tapered elements during operation of said member.

10. In an apparatus of the class described, a rotatable and reciprocable member having a slot extending through the axis thereof and an assembly freely oscillatable in said slot during operation of said member including outwardly projecting strips of abrasive material for the smoothing of internal surfaces, said assembly also including tapered elements associated with said strips for moving the same into outwardly projecting position and means for actuating said tapered elements during operation of said member, said means including a floating bridge and a manually operable member coacting therewith to cause said tapered elements to force said strips outwardly.

11. The method of smoothing an internal non-cylindrical surface composed of a plurality of dissimilar surfaces of generation having a constant diametral length through the common axis of generation of said surfaces, said method comprising adjusting a pair only of honing surfaces radially outwardly into working contact with said internal surface, said honing surfaces being maintained in parallelism in all positions to the common axis of generation and being oscillated without relative movement therebetween in planes passing through said common axis of generation and rotating and reciprocating said honing surfaces relative to said internal bore surface.

12. The method of smoothing an internal surface the contour of which is composed of a plurality of dissimilar surfaces all having a common axis of generation and the diameters of which passing through said common axis are all of con-

11

stant length, said method comprising adjusting a pair only of honing surfaces radially outwardly into pressure relationship with said internal surface throughout the length thereof, holding said honing surfaces in relatively fixed spaced parallel relationship to the common axis of generation but freely oscillatable in all diametral planes passing through said common axis of generation and rotating and reciprocating said honing surfaces relative to said internal surface while maintaining said honing surfaces at all times parallel to each other and in abrading relationship to said internal surface to smooth the same.

13. In an apparatus of the class described, a rotatable and reciprocable shaft having an axially elongated slot extending transversely there-through, and an assembly confined within the axial length of said slot but freely oscillatable as a unit of fixed diametral length in said slot trans-

12

versely of said shaft during operation thereof, said assembly including a pair of diametrically opposed, outwardly projecting, narrow strips of abrasive material for the smoothing of internal surfaces.

14. In an apparatus for finishing a generated bore the cross section of which is characterized by the diameters through its center of generation being all of the same length, a member rotatable about the axis of generation of said bore and axially reciprocal along said axis, said member being provided with a slot in a plane passing through said axis, and an assembly in said slot oscillatable therein as a unit, said assembly including a pair of opposed parallel abrasive strips to contact the wall of said bore and including means to positively spread said abrasive strips while keeping the same parallel to said axis.

MICHELE CASERTA.
